(57) **CLAIM**

The ornamental design for a linear actuator and control box combination, as shown and described.

DESCRIPTION

FIG. 1 is a perspective top view of a linear actuator and control box combination showing a first embodiment of my design,

FIG. 2 is a perspective bottom view thereof,

FIG. 3 is an elevational right side view thereof,

FIG. 4 is an elevational left side view thereof,

FIG. 5 is a top plan view thereof,

FIG. 6 is a bottom plan view thereof,

FIG. 7 is an elevational front view thereof,

FIG. 8 is an elevational rear view thereof,

FIG. 9 is a perspective top view of a second embodiment thereof,

FIG. 10 is a perspective bottom view thereof,

FIG. 11 is an elevational right side view thereof,

FIG. 12 is an elevational left side view thereof,

FIG. 13 is a top plan view thereof,

FIG. 14 is a bottom plan view thereof,

FIG. 15 is an elevational front view thereof; and,

FIG. 16 is an elevational rear view thereof.

The broken away symbols in the drawings indicate that any portion of the article beyond what is shown forms no part of the claimed design.
